BOX END

Elwood I. Tripp, Seattle, Wash., assignor to I. F. Laucks, Inc., Seattle, Wash., a corporation of Washington

Application April 20, 1935, Serial No. 17,377

2 Claims. (Cl. 217—17)

This invention relates to box ends and the like and to methods of forming the same.

An object of the invention is the provision of a composite box end or like article which is sturdy constructed and inexpensive to manufacture.

A more specific object is the provision of a box end of the character under consideration which may be handled with particular ease.

Another object is the provision of an improved method for the formation of box ends and the like.

Other objects of the invention will in part be obvious and will in part appear hereinafter.

The invention accordingly comprises the several steps and the relation and order of one or more of such steps with respect to each of the others, and the article possessing the features, properties, and the relation of elements, which are exemplified in the following detailed disclosure, and the scope of the application of which will be indicated in the claims.

For a fuller understanding of the nature and objects of the invention reference should be had to the following detailed description taken in connection with the accompanying drawing, in which:

Figure 1 is a perspective view of an embodiment of the invention in the form of a blank from which box ends may be formed;

Fig. 2 is an end view of a box end formed therefrom;

Fig. 3 is a top view of the construction ready for the reception of the splines;

Fig. 4 is a fragmentary perspective view illustrating a modification;

Fig. 5 is a similar view illustrating a further modification; and

Fig. 6 is a similar view showing another modified form.

While assemblies of a variety of different types have been proposed for use as ends for orange boxes and uses of similar nature, and while it is well recognized that such constructions offer an excellent field for the utilization of otherwise waste pieces of lumber; no construction which is entirely satisfactory from the standpoints of strength, ease of formation and effectiveness for the purposes intended is available. Uniting means such as end members, metal clips, etc., have been utilized, but these are subject to various drawbacks, including lack of effectiveness, lack of sturdiness in the construction, or difficulties in formation. Furthermore, the ordinary constructions of this type are formed with a smooth surface which makes handling of the box-

end or the like, or of a box or other article embodying the same a relatively difficult matter.

With the foregoing and other considerations in view, the invention contemplates the provision of a simple and sturdy box end or the like in which the parts are held together with particular effectiveness and without the use of clips or like connecting means, and in its more specific aspects contemplates the provision of uniting means which facilitates the handling of a box-end of a box including the same.

In accordance with the invention, a plurality of pieces of wood are disposed one against the other, ordinarily without gluing, and a continuous groove, preferably a plurality of grooves, extending from one piece to another, is formed along a side face of the assembly. In each groove there is disposed uniting means, ordinarily in the form of a wooden spline which is secured in the groove. Desirably, the spline is secured both by gluing and by a tight fit. A construction of this sort provides a sturdy and highly satisfactory box-end which can be formed with extreme ease from pieces of lumber which are otherwise not readily utilizable. If the pieces are thick, as is ordinarily the case, the assembly is grooved on the opposite side faces, splines glued therein, and the assembly sawed thru the middle so as to provide a pair of box-ends. Preferably a plurality of grooves, ordinarily two, are provided in each surface. Desirably, the splines will extend outwardly beyond the faces of the pieces so as to provide handle-positions whereby the box-ends or boxes formed thereof may be handled.

It will be appreciated that while the invention is designed primarily for the formation of box-ends, it is adapted for the formation of other parts of boxes and for a wide variety of constructions wherein a secure but relatively rough union of one or more pieces of wood to provide a generally sheet-like member or other construction which is elongated in one direction or another is desired.

In Fig. 1, there is exemplified a blank embodying the invention and adapted for the provision of box ends. As will be seen, this comprises wooden pieces 10, 11, 12, 13 and 14 which may be formed of any readily available lumber and may be of varying sizes in one direction. These are laid so that one edge of each contacts an edge of an adjacent piece and are formed with continuous grooves 15 and 16 in one of the wide faces of the assembly and continuous grooves 17 and 18 in the opposite face. In each groove there is glued a wooden spline 19 so as to securely unite

the pieces. Preferably, the spline is of such size that it will have a good tight fit in the groove. This construction in itself unites the members, and when utilized in conjunction with glue provides good mechanical strength even before the glue has set, and accordingly a blank can be sawed into box-ends, or a blank, box-end, or other article handled, immediately after assembly. In order to provide grip portions beyond the wide surface of the pieces, each spline extends externally of the groove as indicated at 20. The splines 19 as exemplified project out of the groove throughout their length, but by an amount less than one half the depth of the spline, however, so as to provide an especially compact and advantageous assembly. The externally extending portions 20 serve not only to facilitate handling, but have the additional advantage that they protect a label placed on the portion of the surface between them.

In the formation of this blank, the pieces 10-14 are disposed side by side and the grooves 15-18 are cut out therefrom, preferably after they have been assembled. Desirably, the corners of the grooves are rounded as indicated at 21 to facilitate the entry of the splines. Thereupon glue is provided within the grooves, although in certain instances it may be provided instead or in addition upon the inner surface of the splines. The splines are then pressed securely into the grooves. Thereupon box-ends such as shown in Fig. 2 may be readily provided by re-sawing the blank on the plane indicated by the dot-and-dash line in Fig. 1. As will be apparent, box-ends or other articles may be provided without sawing in instances where a thicker article is desired or where thinner stock is used. Ordinarily in such a case the assembly will be grooved only on one of its side faces. Preferably, two parallel splines are provided on the same side of the article to assure that the pieces will be held firmly together, but the invention in its broader aspect contemplates the provision of one, three or any other desired number of splines or other reinforcing means. Again, while the grooves and splines generally extend into each of the pieces of which the assembly is formed, the splines uniting various pairs of pieces may be staggered or otherwise arranged in certain instances. Furthermore the shape and character of the grooves and of the uniting means may be varied as desired.

In order to provide a particularly sturdy construction, the splines or other reinforcing means may extend laterally as well as externally of the grooves. When they are so extended to an edge of the article, they serve also to reinforce this edge. A construction of this character is shown in Fig. 4. This construction is generally similar to that of Fig. 1, the corresponding parts being distinguished by the subscript *a*. The splines 19a have a portion 22 extending externally of the grooves in which the splines are set and extending also laterally of the grooves to the corner of the article as indicated at 23. This not only forms a particularly strong construction, but also 65 a construction which is reinforced at its corners.

As will be apparent, glue may be applied between the portions 23 and the pieces 10a and 11a, if desired. When glue is so applied, tendencies of the lateral portion of the splines to split are minimized, and even when splitting does occur, the lateral portion will be held in place.

In Fig. 5, there is shown a similar construction wherein the parts are generally similar, being distinguished by the subscript *b*. The splines 19b are formed with external portions 24 extending laterally to a corner of the article as indicated at 25 and also extending in the opposite direction as indicated at 26 to provide a T-shaped construction.

It will be understood that while the provision of external portions on the splines is a desirable feature of the invention for many purposes, there will be instances in which a smooth surfaced article is desirable. In such cases there may be utilized a construction such as shown in Fig. 6 wherein the parts are generally similar to those shown in Fig. 1, but are distinguished by the subscript *c*. In this instance, the splines 19c are of the same size as the groove, and fit entirely within the same so that they have no external portion.

It will thus be seen that the invention provides a box-end or similar article which has a maximum of structural strength consistent with economy and simplicity, and having various advantageous features, and that it also provides an exceedingly simple and efficient method for forming flat articles adapted for use as box-ends and other purposes.

Since certain changes in carrying out the above method, and certain modifications in the article which embody the invention may be made without departing from its scope, it is intended that all matter contained in the above description or shown in the accompanying drawing shall be interpreted as illustrative and not in a limiting sense.

The invention claimed is:

1. A preformed box-end or the like comprising a plurality of pieces of wood disposed side by side so as to present an exposed surface, a groove in said surface extending transversely of the pieces, and a wooden uniting member in said groove and having a portion extending externally of said groove so that it projects beyond said surface and including a projection extending laterally to the edge of the article so as to provide a corner therefor, the lateral portion being glued to the face of the assembly.

2. A preformed box-end or the like comprising a plurality of pieces of wood disposed side by side so as to present an exposed surface, a groove in said surface extending transversely of the pieces, and a wooden uniting member in said groove and having a portion extending externally of said groove so that it projects beyond said surface and including a projection extending laterally to the edge of the article so as to provide a corner therefor.

ELWOOD I. TRIPP.
